UNITED STATES PATENT OFFICE.

JOHN ELOV ENGLESSON, OF KARLSKRONA, SWEDEN, ASSIGNOR, BY MESNE ASSIGNMENTS, TO ALLIS-CHALMERS MANUFACTURING COMPANY, A CORPORATION OF DELAWARE.

PRIME-MOVER-POWER-LIMITING DEVICE.

1,090,520.

Specification of Letters Patent. Patented Mar. 17, 1914.

Application filed June 27, 1912. Serial No. 706,308.

To all whom it may concern:

Be it known that I, JOHN ELOV ENGLESSON, a subject of the King of Sweden, residing at Karlskrona, Sweden, have invented 5 certain new and useful Improvements in Prime-Mover-Power-Limiting Devices, of which the following is a specification.

This invention relates to devices for limiting the power furnished by a prime mover.

10 The object of the invention is to limit the power furnished by a prime mover.

The invention is applicable generally to governors for prime movers of any kind but is specifically illustrated in the accompanying 15 drawing as applied to a governor for controlling the gate in the pipe line of a water wheel.

This invention is adapted for use where the head of water is variable and where an 20 increase in the head might so increase the power of the unit as to endanger the electrical machinery driven thereby. In such a case the device is applied to limit the power to the maximum safe amount within the 25 heating limit of the electrical machinery.

The invention is also applicable to cases where there is likely to be a shortage of water supplied to the prime mover and where if the amount of water used by the 30 prime mover is too great the head would be decreased below the proper amount.

This invention is also adapted for use in cases where only a part of the available power of the prime mover is to be used, as 35 where only up to a certain maximum amount of power is sold. In such cases if a consumer is carrying a load which is in excess of this maximum, the power furnished him will be limited to this maximum and 40 the consumer will thereby automatically be forced to himself furnish the excess over said maximum of power required. In these cases it is necessary that the unit be furnishing power to this consumer alone.

45 One embodiment of the invention is illustrated in the accompanying drawing in which the figure diagrammatically shows the application thereof to the main valve in the pipe line furnishing water to a water 50 wheel not shown.

Referring to the drawing, the pipe line 51 has a main valve or gate 29 therein pivotally mounted, having a crank arm 30 connected by a connecting rod 101 to the piston

rod 26 carrying the piston 28 of a motor 55 27 connected by pipes 19, 20, to the valve casing 14 in which a valve 18 reciprocates. The valve casing 14 is supplied with operating liquid through pipe 16 and has exhaust pipes 15, 17, for discharging liquid 60 therefrom. The valve 18 has collars 6, 7, fixed to its stem 5. The cross head 8 slides on stem 5 between collars 6, 7, and is pivotally connected to one end of floating lever 3 which is pivotally connected intermediate 65 its ends to the collar 2 of a speed responsive means here shown as flyball 1. A spring 9 is mounted on valve stem 5 between collar 6 and cross head 8. This constitutes a lost-motion connection between the valve 18 and 70 the flyball 1. The opposite end of floating lever 3 is pivotally connected to piston rod 102 which is connected through a secondary compensator 103 and link 4 to the bell crank lever 24, 25, pivotally mounted on a 75 support 104. The arm 25 of the bell crank lever is connected to the piston rod 26 by connecting rod 105. This secondary compensating device 103 is specifically described and claimed in a copending application 80 Serial No. 706,312, filed June 27, 1912. The T-lever 106 of the compensating device 103 is pivotally connected at one end of the T to support 107 and at the other end of the T to mechanism within the casing of the 85 compensating device 103 and slides at its lower end through crosshead 108 adjustably slidably on arm 25 of the bell crank lever, which cross head is fixed thereto by set screw 109. The linkage connection generally from the right hand end of the piston rod 26 to the right hand end of floating lever 3 constitutes a primary compensating device for returning the valves 18 to mid position. The secondary compensating device 103 compensates the speed changes induced by the primary compensating device.

Bell crank lever 24, 25, carries a third arm 23 pivotally connected to a crosshead 21 adjustably slidable in slot 110 of link 13 100 by means of a screw 111 rotatable only in link 13 by means of handwheel 22 and screwing through crosshead 21. Link 13 connects at its other end to bell crank lever 10, 12, pivotally mounted on support 112. The 105 outer end of arm 10 of bell crank lever 10, 12, is located directly underneath collar 26 and serves as a stop for the downward

movement of said collar and valve stem 5 to which it is connected. Hand-wheel 22 is manually adjusted to locate crosshead 21 within the slot 110 in such a position that 5 with piston 28 in position corresponding to the desired maximum opening of main gate 29, the end of arm 10 of bell crank lever 10, 12, will be in contact with collar 6 on the valve stem 5, with the valve 18 in mid-position.

With the device so adjusted and the prime mover running at normal speed, it is now supposed that an additional load is thrown upon the prime mover. The consequence is 15 that the speed of flyball 1 will cause collar 2 to be lowered, and as the righthand end of floating lever 3 at this time constitutes a fulcrum, the crosshead 8 will be lowered, thereby compressing spring 9 between it and 20 the collar 6, and no motion of the valve stem 5 and valve 18 will be produced because prevented by the arm 10 of bell crank lever 10, 12. The power furnished by the prime mover will therefore remain within the 25 limit set.

Assume that the main gate 29 is in position corresponding to less than the maximum load to be limited by the device. In such case the arm 10 of bell crank lever 10, 30 12, will be in such position as to be spaced from collar 6. Upon an increase in load under such circumstances, the speed of flyball 1 will be decreased, thus lowering collar 2 and crosshead 8, transmitting the 35 downward motion through spring 9, the collar 6 and valve stem 5, thus moving valve 18 downwardly, letting fluid pressure in through pipes 16, 20, to the right hand end of motor 27 and exhausting fluid 40 through pipes 19 and 15 from the left hand end of the motor 27. Piston 28 will therefore move to the left, thus opening main valve 29 to furnish more water to the water wheel to bring the speed up to normal under the increased load. At the same time 45 the motion of piston 28 to the left will be communicated through the primary compensating device to depress the right hand end of floating lever 3 to return valve 18 to mid-position by bringing the crosshead 8 into positive contact with the collar 7 to raise same.

If the increased load is within the allowable limit, piston 28 will not have moved 55 arm 10 of bell crank lever 10, 12, to the position where it contacts with collar 6, so that there will in this case be no limitation upon the power furnished to meet the increased load. But should the increased load 60 be beyond the allowable limit, then piston 28 will move only so far to the left as to bring arm 10 into contact with collar 6, at the time the primary compensating device has completely returned the valve 18 to mid-position. It will thus be seen that it is im-

possible to move piston 28 to the left beyond a desired limiting position corresponding to the limiting position of main valve 29. The piston 28, rods 26, 105, crank lever 23, 24, 25, and link 13, constitute agencies controlled by the valve 18 and adapted to position the stop arm 10.

In cases where the load decreases, the increased speed of flyball 1 will raise collar 2 and the left hand end of lever 3, thus elevating crosshead 8, which motion is communicated to collar 7 and rod 5 to valve 18, thus placing the motor 27 in condition for operating its piston 28 to the right, thereby throttling main valve 29. This action is 75 again compensated through the primary compensating device to move the right hand end of floating lever 3 upwardly, thereby lowering valve 18 to central position through crosshead 8, spring 9, collar 6 and 80 valve stem 5.

It will thus be seen that by this invention no objectionable force is placed upon the flyball collar 2 and the desired limit of power is secured without necessitating a 85 change in position of flyball collar 2.

It should be understood that it is not desired to be limited to the exact detail of construction shown and described, for obvious modifications will occur to a person 95 skilled in the art.

It is claimed and desired to secure by Letters Patent,—

1. In an indirect governor for a prime mover, a speed responsive means, a motor 100 for actuating the main valve of the prime mover, a means for controlling said motor, a lost motion connection between said speed responsive means and said motor controlling means, and a stop positioned by said motor, and, without limiting the motion of said speed responsive means, limiting the motion of said controlling means which said motion, if permitted, would set the motor for farther opening of said main valve.

2. In an indirect governor for a prime mover, a speed responsive means, a motor for actuating the main valve of said prime mover, a means for controlling said motor, means connecting said controlling means to said speed responsive means, said connecting means being positive in one direction and yieldable in the opposite direction, and a stop positioned by said motor, and, without limiting the motion of said speed responsive 115 means, limiting the motion of said controlling means which said motion, if permitted, would set the motor for farther opening of said main valve.

3. In an indirect governor for a prime 125 mover, a speed responsive means, a motor for actuating the main valve of the prime mover, a means for controlling said motor, said means being governed by said speed responsive means, and means acting directly 130

on said controlling means for preventing the valve from assuming a position beyond a predetermined limiting position.

4. In an indirect governor for a prime mover, a speed responsive means, a motor for actuating the main valve of the prime mover, a means for controlling said motor, a lost-motion connection between said speed responsive means and said controlling means, and motor affected means acting directly on said controlling means for preventing the valve from assuming a position beyond a predetermined limiting position.

5. In combination with a prime mover main valve for controlling flow of fluid to said prime mover, a speed responsive means, a lost-motion connection between said speed responsive means and said main valve and adapted to determine the position of said main valve, and a stop for said lost-motion connection.

6. In combination, a valve, a speed responsive means for actuating said valve, agencies controlled by said valve, and a stop for said valve positioned by said agencies, 25 said speed responsive means remaining free to move when said valve is stopped.

7. In combination, a valve, a speed responsive means for actuating said valve, agencies controlled by said valve, a stop for said valve normally positioned by said agencies, and manually operable means for positioning said stop, said speed responsive means remaining free to move when said valve is stopped. 35

In testimony whereof, the signature of the inventor is affixed hereto in the presence of two witnesses.
